FOOTBALL DOWN MARKER AND INDICATOR

William F. Musch and Russell S. Katz, Hamilton,
Ohio; said Katz assignor to said Musch

Application July 9, 1948, Serial No. 37,736

3 Claims. (Cl. 177—329)

1

This invention relates to sporting equipment, and is particularly directed to a combined down marker and indicator for use by the officials in football games.

The football rules provide that one of the assistant linesmen follows the progress of the ball, as it is advanced by the opposing teams, by carrying a marker along the side line to indicate the position of the ball. This marker is retained in position during play so that the ball may be returned to its former location in the event that an illegal play occurs or a forward pass is attempted and not completed. After each play, the marker is moved along the side line to a position corresponding to the new location of the ball. By comparing the position of the marker with respect to a ten-yard marker also located on the side lines, the officials and players can determine the yardage which must be gained during the remaining downs in the series. The marker is also designed to function as a down marker and carries means for indicating the correct down to the players.

Customarily, the type of marker used has been a metal staff, having a pointed portion at its lower end, which can be imbedded in the earth. The top of the staff is provided with a rectangular block having four vertical faces. Each face carries a number which indicates a separate down, and the official arranges the block after each play so that the face bearing the number corresponding to the correct down is exposed toward the field, thereby enabling the players and officials to determine the number of downs remaining in the series.

This type of down indicator has not proved to be satisfactory in the past, primarily because only the players and officials on the field can see the numerals. Many playing fields do not have score boards and the spectators have no way of determining the number of downs that have been played except by reference to the down marker. Most spectators cannot see the down numeral at all since it is clearly visible only from certain parts of the stadium.

It is an object of this invention to provide a down marker embodying a plurality of elevated colored signal lights, which may be selectively energized to indicate the correct down, and which is capable of being seen from any part of the stadium during rainy or foggy weather and under the most adverse conditions of visibility.

An additional aim is to provide a down marker employing means to effectively disperse light ema-

2

nating from electrical signal lights contained therein through a 360° dispersion.

It is a further object of this invention to provide a football down marker of rugged construction, yet capable of being partially disassembled, thereby enabling the compact storage of its several parts while it is being transported.

In accordance with these objectives, the present invention contemplates an elongated vertical body member, having a series of colored signal lights arranged in vertically spaced relationship in the upper portion of the body, a simple electrical circuit including a source of electrical energy disposed within the body, and switch means for energizing said lights. Each of the lights represents a different down of the series, and the official actuates the switches after each play, so that the correct light or number of lights is turned on, thus indicating to the players and spectators the correct down. A lens system directs the rays reflected from the electric lights through openings in the body member, and cooperates with a system of mirrors to disperse the rays through a 360° horizontal dispersion. The lens and mirror system, along with the light bulbs, are enclosed completely within a tubular body member, the construction thus affording maximum protection for the lights and the attendant light-dispersal system, in the event the marker is thrown violently to the ground as the play moves toward or crosses the side line.

In the drawings,

Figure 1 is a vertical elevation of the assembled down marker of this invention.

Figure 2 is a vertical elevation of the detachable upper portion of the down marker enlarged to show the signal lights and their controlling switch panel.

Figure 3 is a vertical sectional view taken along line 3—3 of Figure 2.

Figure 4 is a horizontal sectional view taken on line 4—4 of Figure 2.

Figure 5 is a horizontal sectional view taken through the switch panel along line 5—5 of Figure 2.

Figure 6 is a vertical fragmentary view, partially in section, of the lower portion of the improved down marker showing part of the upper member in operative association therewith.

Figure 7 is a vertical sectional view taken on line 7—7 of Figure 2 through the central portion of the down marker showing the electrical connections between the batteries, the switch panel and the upper member.

Referring to the drawings, the assembled down

marker is shown in Figure 1 and comprises a lower staff 10, having a spiked end portion 11 which is pointed to permit easy insertion into hard or frozen ground, an upper barrel portion 12 carrying four signal lights 13, 14, 15 and 16, and an exposed switch panel 17 carrying four toggle switches 18 through 21. Each switch controls a separate light and all are connected in common to a number of dry cell batteries carried in the staff 10. Near the base of the staff, a circular ground plate 22 is fixed to serve as a stabilizing base, and holds the marker erect when unattended.

In this embodiment, the lights each represent different downs in ascending order. Thus, when the first down is to be played, the lowest light 13 is energized by operation of the toggle switch 18. When the second down is to be played, the switch 19 is thrown, illuminating the light 14 etc. It will be noted that the spectators and players can readily determine the correct down by simply counting the number of lights, even though they are at too far a distance to ascertain whether the lowest light or one of the intermediate lights is turned on. The lights are also arranged with a substantial space between them so that each light is clearly defined and can be readily distinguished when seen from a distance. Preferably the lower three lights are green, indicating that additional plays remain after the next down, while the upper light is red to warn the players that the fourth down is ensuing. Obviously, different colored lights may be used if desired.

Detailed construction of the upper member 12 is best seen in Figures 2 and 3. This member is comprised of a tubular barrel 12 having a detachably-connected end cap 23 which, in the embodiment shown, is in screw-threaded engagement with the barrel. It will be seen that since the end cap is hollow, it cooperates with an end closure plate 24 to provide a convenient storage chamber for spare light bulbs and batteries. The barrel is provided with four groups of windows 25 formed at vertically spaced intervals in its side-walls, and arranged adjacent the several lights to permit the light to emanate in all directions from the barrel. To prevent the connecting posts 26, which subside between the windows and maintain the barrel in integral connection, from creating blind spots by interfering with the passage of the light, the interior of each post is equipped with metal mirrors 27 arranged in angular relationship. Each post preferably has two of these mirrors, which are so disposed as to cooperate with the mirrors on the other posts to reflect the light into zones which otherwise would be shielded by the posts from receiving light.

The lights comprise bulbs 28 mounted in sockets 29 which, in turn, are mounted in transverse support plates 30 affixed to the barrel by means of screws 31. Mounted on the plates 30, coaxially of the barrel, are cylindrical housings 32, which contain basin-type reflectors 33. The wall of each housing is flattened along an upper rim to seat the base of the lamp lenses 34, which are secured to the housings by means of caps 35, fitting over annular flanges 36 formed on the base portions of the lenses, and in screw-threaded engagement with the outer walls of the housings 32. It will be observed that the preferred embodiment is of particularly rugged construction and affords maximum protection to the frangible lens and bulb structure. The light bulbs and lens reside within and are protected by the barrel member and are not prone to being broken easily.

in the event the member is thrown violently to the ground.

A particularly noteworthy feature of this invention resides in the lens structure 34. The lens is of generally conical outline and is not hollow, as are conventional lenses, but solid throughout, being preferably formed of any suitable light-transmitting plastic. A typical lens material of this type is the commercial plastic "Lucite." A plurality of annular V-grooves are formed on the external surface of the lens. In the preferred embodiment, the sides of these grooves are disposed substantially at a 45° angle to the vertical axis of the conical lens in such a manner that they intercept the parallel light beams coming from the reflector 33, bend them through an angle of approximately 90° and disperse them radially through 360°. However, the angular disposition of the groove faces must naturally be varied in accordance with the type of lens material employed, to achieve maximum refractive efficiency. Thus the light beams which would normally ascend vertically are refracted horizontally in all directions and provide a maximum effective use of the light source. The diminishing diameter of the cone operates to offset each groove in respect to the adjacent grooves, thereby assuring the presentation of an angled groove for refracting substantially all of the light beams coming from the reflector.

As best seen in Figure 7, the lower portion of the barrel member 12 is connected to the staff 10 through the panel 17 by means of screws 38 which are fastened to a flange 39 provided on the switch panel 17. The lower portion of this panel is formed into a hollow tubular member 41 proportioned for telescoping engagement with the upper end of the staff 10 and carries diametrically opposed thumb screws 42 which are adapted for interlocking engagement with bayonet slots 43 carried in the staff wall. Thus, the switch panel and barrel may be quickly detached from the staff member by loosening the thumb screws and disengaging the tubular member 41 from the hollow staff member 10 when it is desired to disassemble the down marker for storage or shipment or to replace the batteries.

The switches are mounted on the panel 17, and are surrounded by a rectangular wall 44 which serves to protect the switches in the event the marker is thrown to the ground or dropped in transit. The switches themselves may be of standard manufacture and comprise contact boxes 45 integrally mounting screw-threaded studs 46 which extend through suitable holes 47 in the panel and expose the toggles 18 through 21 on the open side of the panel carrier. Each switch assembly is secured to the panel by a flat nut 48 seated on the panel and in screw-threaded engagement with the stud 46. At the rear of the panel carrier, a cover plate 49 is detachably fastened by means of screws 50 to ribs 51 formed in the carrier. When it is necessary to repair or adjust the switches or their attendant wiring, the back may be removed by loosening the screws thus permitting access to the contact boxes. If necessary, the entire switch may then be removed by loosening the switch nut. The extreme bottom portion of the panel carrier is provided with a button contact 52 which is electrically insulated from the carrier by means of an insulating member 53. This button is in electrical contact with a number of dry cell batteries 54 arranged in series connection within the hollow staff. The batteries are maintained in electrical commun-

cation with each other and with the button 52 by means of a coil spring 55 under compression between the batteries and a metal plate 55a joined to the staff walls.

The electrical circuit is of conventional arrangement and is generally similar to the circuit of the commercial flashlight. A lead 56 is taken from the button contact 52 and carried through a hole 57 formed in the panel carrier from whence branch leads 58, 59, 60 and 61 proceed to the contact boxes of the respective toggle switches. Each of these branch leads emerges from the other side of the contact box, and all are drawn upwardly through a hole 62 in the upper portion of the switch housing. Lead 58 is connected to the lamp socket of light 13, while the other leads 15 continue upwardly, extending through holes 63 formed in the bracket 30.

In the preferred construction, these leads 59, 60 and 61 are introduced into the narrow channels formed between the wall posts and the angulated mirrors (see Figure 4). The channels thus formed by the mirrors and side posts serve to conceal, enclose and protect the wires. Thereafter, the branch leads are connected with their respective lamp sockets 14, 15 and 16 in much the same manner as described with reference to lamp 13. Each of the lamp brackets 30 is a conductor and communicates with the tubular wall of the upper member 12, thereby grounding the circuit for each lamp through the outside wall, down through the panel carried to the staff 10 and finally to bracket 56 which seats the spring conductor 55. It will be seen that each lamp is contained in an individual electrical circuit, all of the circuits using a common source of electrical power and a common ground element. Nevertheless, each circuit may be severally and selectively energized independently or concurrently with the other circuits by means of the respective toggle switches.

Having described our invention, we claim:

1. A football down marker and indicator comprising a body member having four vertically spaced groups of radial apertures, four electric lights arranged within said body member, each of said lights being disposed below a group of

10 apertures and having a conically shaped lens of light-transmitting material configurated to present a surface of annular V-shaped grooves adapted to direct vertical light rays emanating from said electric lights horizontally outward through said apertures and means for selectively energizing said electric lights.

2. A portable down marker and indicator comprising a body member having a spiked end portion adapted to be inserted in the earth, said body member having openings spaced vertically from one another along the upper portion thereof, a signal light spaced vertically from each of said openings, said signal lights being disposed in the body member, and a lens of substantially conical configuration positioned in each of said openings, the bases of said lenses being disposed toward the signal lights whereby the light beams will be directed horizontally through the openings.

20 3. A portable down marker and indicator comprising an elongated body member including a lower staff portion having a spiked end adapted to be removably inserted in the earth and an upper barrel portion, said barrel portion being divided into sections spaced vertically from one another by posts with openings in the body member adjacent the posts, a signal light adjacent each of said openings and mirror means on the inner surfaces of the posts for reflecting light 25 horizontally through the openings.
